POURING SPOUT

William H. Trexler, Jr., 735 E. Cedar Extension,
Ravenna, Ohio

Filed July 21, 1960, Ser. No. 61,458

Term of patent 14 years

(Cl. D58—26)

FIG.1

FIG. 2

FIG.3

Fig. 1 is a top plan view of a pouring spout, embodying my new design;

Fig. 2 is a side elevational view thereof; and

Fig. 3 is a bottom plan view thereof.

The drawing is stippled to show a difference in color.

I claim:

The ornamental design for a pouring spout, as shown and described.
